UNITED STATES PATENT OFFICE.

VERNON HOXIE, OF ADRIAN, MICHIGAN.

STAPLE FORMING AND DISCHARGING MECHANISM.

942,906.

Specification of Letters Patent. Patented Dec. 14, 1909.

Application filed May 29, 1909. Serial No. 499,206.

To all whom it may concern:

Be it known that I, VERNON HOXIE, a citizen of the United States, and a resident of Adrian, in the county of Lenawee and State 5 of Michigan, have invented a certain new and useful Staple Forming and Discharging Mechanism; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to mechanism for use in conjunction with wire fabric machines or the like for successively forming staples from sections of wire intermittently fed 20 thereto, discharging the formed staples from such mechanism, and clamping them about the intersecting portions of the fabric being woven.

The object of my invention is to improve 25 upon the mechanism described and claimed in my former application Serial No. 477,932, filed February 15, 1909, whereby to lessen the cost of manufacture and instalment thereof, to simplify its construction, and increase the efficiency of its operation.

The operation, construction and arrangement of the parts of the invention, are fully described in the following specification, and while in its broader aspect it is susceptible 35 of numerous modifications, a preferred embodiment of the same is illustrated in the accompanying drawings, in which,—

Figures 1 and 2 are reverse side elevations of the mechanism comprising my invention, 40 with the reciprocatory staple-forming and driving parts at the limit of their rearward movements. Fig. 3 is an enlarged plan view of the staple-forming cylinder and its shaft. Fig. 4 is an enlarged top plan view of the 45 rear end portion of the mechanism looking in the direction of the arrow in Fig. 1. Fig. 5 is a rear end elevation of the same, and Fig. 6 is a vertical longitudinal section on the line $\alpha\alpha$ in Fig. 4.

Referring to the drawings, 1 designates the holder thereof, which has its upper surface preferably inclined, as shown, and vertically grooved or recessed from its rear end forwardly, as at 2, to receive the plunger 3. 50 This plunger is shown as being provided in its sides with longitudinal grooves 4 for re-

ceiving complementary guide ribs 5 formed on the walls of the groove 2, and is provided at its forward end with the staple-discharge nose 6, which works into a staple-discharge 60 way or shallow extension 7 of the groove 2.

Mounted at the forward end of the holder 1 immediately above the staple-discharge way 7 therein is a staple cylinder or rotary staple magazine 8, which is disposed longitudinally of said discharge-way and is carried by a shaft 9. This shaft has its forward end journaled in bearings 10 and 11, which rise from the top of the forward end portion of the holder 1 and are disposed on opposite 70 sides of the cylinder 8. A collar 12 on the shaft to the rear of the cylinder coacts with the forward side of the bearing 11 to prevent rearward movements of the shaft relative to the bearings. The cylinder 8 is provided around its circumference with a plurality of equidistantly-spaced longitudinally-extending grooves 13, in the present case four in number, the side walls of which are preferably concaved or half rounded to 80 adapt each to hold a staple drawn therein against lateral withdrawal therefrom. When the cylinder is turned as hereinafter described these grooves successively move into register with the staple-discharge way 7. 85

The wire thread from which the staples are formed is shown at α in Fig. 2, and feeds upwardly through a cutaway portion or feed-opening 14 in one side of the holder 1 at the forward end thereof and an opening 90 15 through a broadened portion 16^a at the lower inner edge of a bar or plate 16, and thence through an opening or cutaway portion 17 in advance of a groove 13 in the contiguous side of the cylinder 8. The bar 95 or plate 16 is carried by one side of the holder for reciprocatory movements in a plane parallel to the axis of the cylinder 8, being held to the holder for such movements by an arm 11^a rising from the bearing 11 100 and hooking over the upper edge of the bar and by a complementary tongue and groove engagement at the lower edge of the bar, as shown in Figs. 2 and 5. On a rearward movement of the bar 16 from its limit of 105 forward movement a section of wire, which was previously fed by any suitable mechanism to the opening 17 of the holder in advance of a registering groove 13 in the cylinder 8, is severed from its thread due to the 110 opposed shearing action of the upper end of the wall of the opening 15 in the bar 16

and the fixed cutter-die 18 at the lower end of the opening 17, see Fig. 2. As the section is severed from its thread it is engaged midway between its ends by a stud 19, projecting inwardly from the forward end portion of the bar 16 and drawn thereby within the registering groove 13 in the cylinder side and formed into a staple *b* by the coöperating action of such stud and the side walls 10 of the groove.

Rising from the rear end portion of the plunger 3 and movable therewith is a block 20, which carries a pawl 21 at the side thereof contiguous to the bar or plate 16. This 15 pawl is mounted on a stud 22 for vertical oscillatory movements, and has its free end provided with a cross-head 23, one end of which is adapted to coöperate with a notch 24 in the upper edge of the bar 16 to force 20 such bar forward during a portion of the forward movement of the plunger, while its other end is adapted to ride over a cam 25 which effects a release of such cross-head from the notch 24 at a predetermined point 25 in a forward stroke of the plunger. The cam 25 rises from the side of the holder 1 opposed to the bar 16 and is positioned to effect a release of the pawl 21 from the notch 24 when the bar 16 has completed its forward movement, which is less than that of 30 the plunger 3. A spring 26 is carried by the block 20 and acts on the pawl 21 to normally hold it in engagement with the notch 24.

35 The rearward movements of the bar 16 are actuated from the plunger 3 by reason of the head of the stud 22, which carries the pawl 21, working in the longitudinally-extending slot 28 in such bar and engaging 40 the rear end thereof at a predetermined point in the rearward movement of the plunger whereby to move the bar therewith during the remainder of such rearward movement.

45 The means employed for imparting intermittent rotation to the cylinder for the purpose of successively moving the grooves 13 thereof into register with the discharge-way 7, consists in extending the rear end of the 50 shaft 9 loosely through the block 20, whereby such block has longitudinal movements thereover, and providing a spring-pressed pin 29 in the block above the shaft and a series of grooves 30 longitudinally in the 55 surface of the shaft for such pin to successively travel in as it is moved backward and forward thereon. The grooves 30 correspond in number to the number of grooves 13 in the cylinder 8, and each comprises the two 60 straight longitudinally-extending portions *c* and *d* and the intermediate laterally-curved connecting portion *e*. The forward portion *d* of each groove is disposed one-quarter of a turn around the shaft from the rear portion 65 *c* thereof, should four grooves be provided

as in the present case, and stands in longitudinal alinement with the rear portion *c* of the successive groove. On a forward stroke of the plunger the pin 29 on passing through the curved portion *e* of a groove effects a 70 sufficient turning of the shaft 9 and cylinder 8 to move one groove 13 of the cylinder out of register with the discharge-way 7 and the successive groove 13 in register therewith, it of course being understood that the curved 75 portion *e* of each groove 30 is so disposed that a turning of the cylinder 8 is not effected until the bar 16 has moved forward sufficiently to move the staple-forming stud 19 thereon out of a groove 13 in the cylinder. 80 On a rearward movement of the plunger, the pin 29 instead of following the curved portion *e* of the groove in which it is disposed rides up the incline *f* at the rear end of the portion *d* of the groove and then drops into 85 the portion *c* of the succeeding groove and continues its rearward movement therein. The pin 29 has its head mounted in a socket 31 and is yieldingly held depressed by a coiled compression-spring in such socket, as 90 shown in Fig. 6.

32 designates a link which connects the plunger 3 with any suitable actuating means.

In the operation of my invention a length of wire is fed to the holder 1 while the bar or 95 plate 16 is at the limit of its forward movement, or during the period of relative movements of such bar and the plunger 3, which is permitted by reason of the pawl 21 being released from the notch 24 in the bar and the 100 stud 22 working in the slot 28 therein. On a rearward movement of the plunger the pin 29 passes up the incline *f* at the rear end of the portion *d* of the groove 30 in which it is traveling and drops into the portion *c* of 105 the succeeding groove, and during the last portion of such movement the stud 22 carried by the block 20 coacts with the rear end of the slot 28 in the bar 16 and moves such bar therewith. As the bar 16 moves rearwardly with the plunger the fed length of wire is severed from its thread *a* by the shearing action of the cutter 18 and apertured face of the bar 16, and the stud 19 engages such severed section and draws it 115 within the registering groove 13 of the cylinder 10 thereby coöperating with the walls of such groove to form the wire into U-shape. On the reverse or forward movement of the plunger the bar 16 is caused to 120 move forward therewith due to the engagement of the pawl 21 with the notch 24 in the bar, and when such bar has reached the limit of its forward movement the pawl is released from engagement with the notch by the action of the cam 25 on the cross-head 23 of the pawl, thus permitting the plunger to continue the remainder of its forward stroke alone to discharge a staple from the registering groove 13 of the cylinder 10 and from 125 130

the discharge-way 7 and clamp it about the fabric being woven. After the stud 19 has moved out of a groove 13 of the cylinder and before the discharge nose 6 of the plunger 5 has entered a groove 13 in the cylinder, the pin 29 passes through the curved portion *e* of the groove 30 in the extended end of the shaft 9, thus effecting a partial rotation of the cylinder 10 to move the succeeding staple-carrying groove 13 thereof into register with the advancing discharge-nose 6 and at the same time moving an empty groove 13 into register with the staple-forming stud 19 to permit a staple to be drawn therein on the 15 next rearward movement of the bar 16.

I wish it understood that my invention is not limited to any specific construction or arrangement of the parts except in so far as such limitations are specified in the claims.

Having thus described my invention, what I claim as new and desire to secure by Letters Patent, is,—

1. In an apparatus of the class described, the combination of a staple-discharging member, a rotary staple magazine, a shaft carrying said magazine and having longitudinally-extending grooves provided with laterally curved portions and with straight portions connected by such curved portions, 36 each groove having one straight portion in longitudinal register with a straight portion of the succeeding groove, and a pin yieldingly carried by the discharging member and adapted to travel in a groove during one 35 direction of movement of the discharging member and to coöperate with such groove to effect a partial rotation of the magazine and to move from such groove to the succeeding groove during the movement of such 40 member in the opposite direction.

2. In an apparatus of the class described, a holder having a staple discharge-way therein, a shaft mounted adjacent to such discharge-way and parallel thereto, a magazine carried by such shaft and adapted to carry and move staples from forming to discharging position, means movable to coöperate with said magazine to form staples therein, and means movable in said discharge-way for discharging staples from such magazine and having a part adapted to coöperate with said shaft to impart intermittent movements to the magazine when said discharging means is operated.

3. In an apparatus of the class described, the combination of a holder having a staple discharge-way therein, a rotary staple carrying magazine mounted adjacent to such discharge-way and having a part projecting 60 axially therefrom in parallelism with such way, a member movable to coöperate with such magazine to form staples therein, a plunger movable in said discharge-way to discharge staples from such magazine and 65 from said way, said plunger having connec-

tion with said member whereby to impart operative movements thereto and having a part which coöperates with the part projecting from such magazine to intermittently rotate the magazine as the plunger is operated 70 whereby to successively move staples into register with such plunger.

4. In an apparatus of the class described, the combination of a holder having a staple discharge-way therein, a shaft mounted adjacent to such discharge-way in parallelism therewith, a staple magazine carried by such shaft, and mechanism operative to coöperate with said magazine to form staples therein and to coöperate with such shaft to intermittently rotate such magazine to move staples from forming to discharging position and having a part working in said discharge-way to discharge staples from the magazine.

5. In an apparatus of the class described, 85 the combination of a holder having a staple discharge-way therein, a staple magazine carried by such holder adjacent to such discharge-way and having peripheral grooves therein adapted to successively move into 90 register with such discharge-way when the magazine is rotated, a part projecting axially from such magazine in parallelism with such discharge-way, a member operative to coöperate with said magazine to 95 form staples in the grooves thereof, and a plunger movable in said discharge-way to discharge staples from such magazine and having means movable therewith and co-operating with said part to impart intermittent 100 rotary movements to the magazine as the plunger is operated.

6. In an apparatus of the class described, the combination of a holder having a staple discharge-way therein, a shaft carried by the 105 holder and paralleling such discharge-way, a magazine carried by such shaft and adapted to move staples from forming to discharging position, a part adapted to co-operate with such magazine to form staples 110 therein, a plunger movable to discharge staples from the magazine, means carried by the plunger for coöoperating with the shaft to impart intermittent rotary movements to the magazine when the plunger is 115 operated, and means for communicating movements from the plunger to said staple forming member.

7. In an apparatus of the class described, the combination of a holder having a staple discharge-way therein, a magazine mounted adjacent to such discharge-way and having its axis parallel to said discharge-way, said magazine being adapted to move staples from forming to discharging position, a 120 reciprocating member for coöoperating with said magazine to form staples therein, a plunger movable in said discharge-way to discharge staples from such magazine and 125 way, means movable with said plunger and 130

acting on said member to move it in one direction, means movable with said plunger for moving said member in the opposite direction, and means for coöperating with such latter means at a predetermined point in the movement of said member whereby to release such means from engagement with said member to permit a relative movement of said plunger and member, and means for 5 intermittently rotating the magazine to successively move the staples carried thereby into register with the discharge-way.

8. In an apparatus of the class described, the combination of a holder having a discharge-way therein, means for moving staples from forming to discharging position, a reciprocating member coöperating with such means to form staples therein, a plunger movable in said discharge-way to 10 intermittently discharge staples from said means, means actuated by said plunger for moving said member in one direction, means actuated by said plunger for moving said member in the opposite direction, and means 15 adapted to coöperate with said latter means at a predetermined point in the movement of said member to effect a disconnection of said latter means and member to permit the plunger to move independently of such member.

9. In an apparatus of the class described, the combination of a holder having a discharge-way therein, a magazine carried by such holder adjacent to said way and having a part projecting axially therefrom in 20 parallelism with said way, said part having longitudinal and interconnecting grooves, a member operative to coöperate with said 25

magazine to form staples therein, a plunger movable in such discharge-way to discharge 40 staples from said magazine, and means movable with said plunger and coöperating with the grooved portion of said part to impart intermittent rotary movements to the magazine when the plunger is operated. 45

10. In an apparatus of the class described, the combination of a holder having a discharge-way therein, a rotary staple carrying magazine mounted adjacent to such way, means for intermittently rotating such 50 magazine, a member reciprocally movable and adapted to coöperate with such magazine to form staples therein, said member having a longitudinal slot, a plunger movable in said discharge-way to discharge 55 staples from such magazine, a part carried by said plunger and movable in said slot and adapted to act on said member to move it in one direction, a latch member carried by said plunger and adapted to engage said 60 member and impart movement thereto from the plunger in the opposite direction to the movement imparted to such member by said part, and means for acting on said latch to release its engagement at a predetermined 65 point in its movement whereby to permit a movement of the plunger independent of said member.

In testimony whereof, I have hereunto signed my name to this specification in the 70 presence of two subscribing witnesses.

VERNON HOXIE.
